UNITED STATES PATENT OFFICE.

CHARLES O. SNYDER, OF NEW YORK, N. Y.

BRAKE-RIGGING FOR SELF-PROPELLED VEHICLES.

No. 824,215.

Specification of Letters Patent.

Patented June 26, 1906.

Application filed May 9, 1905. Serial No. 259,607.

To all whom it may concern:

Be it known that I, CHARLES O. SNYDER, a citizen of the United States, residing in the city of New York, in the borough of Manhattan and State of New York, have invented certain new and useful Improvements in Brake-Rigging for Self-Propelled Vehicles, of which the following is a full, clear, and exact description.

10 This invention relates to the brake-rigging of self-propelling vehicles.

In that class of vehicles where the brake in the form of a strap or shoes acting upon a drum is applied to the driving-wheels, the 15 axle to which the wheels are fixed is normally surrounded by a non-rotating sleeve to which the vehicle-springs and the brake strap or shoes are secured. When the brake is set, the torsional strain caused by the frictional engagement with the drum is communicated to the sleeve, and consequently to the vehicle-springs attached thereto. This 20 strain constantly recurring tends to loosen, strain, and even break the springs, besides causing that end of the vehicle beneath which the springs lie to hump up and make the riding uncomfortable.

This invention is designed to overcome this defect, and to that end consists in so 30 mounting the stationary members of the brake that the strain referred to is communicated to the body of the vehicle instead of to the sleeve mentioned and at a point where it will be distributed in a downward direction 35 throughout all of the springs of the vehicle.

In the drawings accompanying and forming a part of this specification a form of my invention is illustrated, wherein—

Figure 1 is an elevation of a portion of an 40 automobile, illustrating a practical embodiment of my invention. Fig. 2 is a similar view with the wheel and spring removed and the brake-drum shown in longitudinal section. Fig. 3 is an enlarged view of the end of the 45 brake-carrier, certain parts being broken away and shown in longitudinal section. Fig. 4 is a top plan view of parts shown in Figs. 1 and 2, certain parts being shown in horizontal section; and Fig. 5 is a view from 50 the end in about the line 5 of Fig. 4.

Only such portions of the vehicle have been illustrated as are necessary to a complete understanding of the invention.

The bottom framing member 11 is in the 55 present instance a channel-iron having a web portion 12 and two horizontally-disposed

flanges 13 13. This is the usual floor-beam of the car or carriage and from which the parts are supported. The wheel designated in a general way by 15 may be of any 60 convenient construction, having a brake-drum 16 secured thereto, which brake-drum, in the present instance, is intended for engagement upon the inner perimeter by a pair of brake-shoes 17, each of which constitutes 65 a half-circle, and is provided in the form illustrated with an eye 18 at its lower end. Such eyes are pivoted by means of a pivot member 19, and their upper ends are controlled by a toggle comprising a pair of links 70 190, having suitable connections with the free ends of the shoes. Such links are pivoted at their knuckles to a link 20, which is in turn pivoted to a rock-arm 21, carried by a rock-shaft 22. The rock-shaft 22 and the pivot 75 member 19 are carried by a brake-carrying device 25, which brake-carrying device is, in the present instance, in the nature of a channel-iron or truss, it having a web portion 26 and horizontally-disposed flanges 27 to give 80 it stiffness and rigidity, and for the purpose of lightness it may be of skeleton work, as shown.

The axle 30, to which the wheel is fast and which will be driven in some suitable manner, 85 has a sleeve 31 surrounding it, which sleeve carries a bearing-box 32, containing the usual rollers or other bearing devices for the axle. There is a sleeve 33 loose upon the sleeve 31 and held from longitudinal movement by 90 means of a collar 34. The sleeve 33 has a flange 35, which may be fastened, as by rivets 36, to the end of the brake-carrier and surround an opening 37 in such brake-carrier, which may be concentric with the sleeve 31 95 and axle 30. Assuming that the rear axle is the one illustrated, the brake-carrier will project forwardly and inwardly to the body-beam and be secured thereto in some suitable manner. In the present instance a bracket 100 40, having side members 41 to fit upon the side of the beam, may be secured by means of bolts 42 to the same, a suitable filling 43 being inserted in the hollow portion of the channel-iron to give greater stability to the 105 bracket. The connection between the end of the brake-carrier and the bracket may be by means of a turnbuckle 44, engaging a screw-threaded rod 45 from the end of the carrier, and a screw-threaded rod 46, having 110 an eye 47, surrounding a pivot 48 in the bracket 40. The turnbuckle affords means

of adjustment, and the pivot will permit movement of the carrier when the axle and wheel move vertically with relation to the body. The spring 50 is shown resting upon 5 the sleeve 31 and fastened to the same by means of clips 53. Its forward end is supported by bracket 40 through the link 51 and arm 52. All the parts of the brake controlled by the carrier are concentrically mounted 10 upon the sleeve, and consequently in similar relation to the wheel and its brake parts. The application of the brake will be by means of a lever 55, fast upon the rock-shaft 22, upon moving which to straighten the toggle 15 the brake-shoes will be forced into engagement with the brake-drum. The twisting strain thus brought upon the shoes will now be transmitted to the brake-carrier 25, and this member being pivoted about the axle 20 will tend to swing downward at its forward end, which tendency will be exerted upon the middle of the vehicle-body, and thus distributed evenly throughout the springs. A foot-board 60 may be carried by a bracket 61, also 25 dependent from the bracket 40. By this means one substantial bracket may be attached to the framing member of the vehicle in a strong manner and the multiplicity of attached devices be obviated.

30 In Fig. 3 a bracket 63 is shown for carrying the rock-shaft 22, such bracket being fastened by rivets 64 to the horizontal member of the carrier and by rivets 65 to the web member thereto, and the bracket 66 for carrying the pivot member 19 may be suitably riveted or bolted to the frame of such carrier and receive the enlarged portion 67 of said 35 pivot-pin. The brake-carrying lever 25 will serve to a certain extent as a radius-bar.

Various details of construction may of course be changed as various conditions of employment demand without departing from the spirit of my invention.

Having described my invention, I claim—

1. In a brake-rigging, a rotating brake-drum, a radius-rod attached to the vehicle and extending into proximity to said drum, a shoe pivoted to said radius-rod and extending annularly around said drum, a lever also pivoted to said radius-rod, and having a link connection with said shoe, and means for imparting tension to said lever.

2. In a brake-rigging, a rotating drum, a radius-rod attached to the vehicle-body and extending into proximity to said drum, a pair of brake-shoes pivoted to said radius-rod and extending peripherally around the drum in opposite directions, and a lever also pivoted to said radius-rod and having a pair of link connections to the respective shoes.

3. In a brake-rigging, a rotating drum fixed to the vehicle-wheel, a radius-rod attached to a portion of the vehicle-body and extending into proximity to said drum, said radius-rod being formed of a pair of diverging truss members having an intermediate web with perforations or openings therein, a lever pivoted within said radius-rod, a brake-shoe having a link connection to said lever, and means for pivotally connecting said brake-shoe to said radius-rod.

In witness whereof I subscribe my signature in the presence of two witnesses.

CHARLES O. SNYDER.
